UNITED STATES PATENT OFFICE.

JOHN P. NEFF, OF EAST ORANGE, NEW JERSEY.

CIRCULATING MEANS FOR LOCOMOTIVE-BOILERS.

1,111,916.

Specification of Letters Patent. Patented Sept. 29, 1914.

Application filed September 8, 1913. Serial No. 733,703.

To all whom it may concern:

Be it known that I, JOHN P. NEFF, a citizen of the United States, residing at East Orange, in the county of Essex and State 5 of New Jersey, have invented certain new and useful Improvements in Circulating Means for Locomotive-Boilers, of which the following is a specification.

This invention relates generally to locomotive boilers, and has particularly in view means for increasing the circulation of water within the boiler, which will obviously result in a higher boiler efficiency, since a greater amount of heat will be absorbed by 10 the water due to the improved circulating system, which the present invention provides for.

One of the objects of this invention is to provide a positive mechanical water circulating system, which will force the water in the bottom of the boiler, to the top thereof and thereby obtain better working conditions than can be obtained by relying on the natural circulation set up by the heating of 25 the water alone.

Another object of this invention is to provide a compartment for the coolest or most inactive body of water, which is in communication with the mechanical water circulating system or pump at one end and in direct communication with the front water leg of the boiler at the other or opposite end.

A further object of the invention is to provide increased steaming facilities for the boiler by locating the boiler tubes so that they will not easily become inactive through stoppage by ash and cinder, which is a fault commonly found in the present design of locomotive boilers.

With these and many other objects in view which will more readily appear as the nature of the invention is better understood, the same consists in the novel construction, combination and arrangement of parts hereinafter more fully described, illustrated and claimed.

It will be readily understood that this invention is quite susceptible to a wide range of structural modification without departing from the spirit or scope of the invention, but a preferred and practical embodiment of the invention is shown in the accompanying drawings in which—

Figure 1 is a longitudinal sectional view 55 of a locomotive boiler showing my present invention installed therein. Fig. 2 is a plan

view of the parts shown in Fig. 1 of the drawings. Fig. 3 is a transverse sectional view of the boiler shown in Fig. 1 clearly illustrating the mechanical water circulator. Fig. 4 shows the front elevation of a locomotive smoke box with the water circulating means installed therein. Fig. 5 shows a longitudinal sectional view of the locomotive smoke box shown in Fig. 4.

Like reference characters designate corresponding parts throughout the several figures of the drawings.

In carrying out this invention, no material change is contemplated in the usual form or construction of the locomotive boiler, which is designated in the drawings by the numeral 1. Within the boiler 1 and located near the bottom thereof is a plate or diaphragm 2 extending horizontally across 70 the boiler from side to side, which forms a segmental mixing compartment 3, one end 4 of which is in open communication with the interior of the boiler 1, while the other end 5 is closed by the front flue sheet 6 against 75 which one end of the plate 2 abuts.

Near the forward end of the compartment 3, there is attached the mechanical water circulator designated in its entirety by the numeral 7, and consisting primarily of a conveyor screw 8 having oppositely pitched flights on each side of its center and including the shaft 9, mounted in a tubular casing 10 arranged transversely below the boiler 1. Said casing is provided at each end and in 90 the middle with the vertically disposed flanged necks 11, the center one of which is connected through a full joint connection 12 to the pipe flange 13 on the bottom of the 95 boiler 1, thus establishing the casing 10 in communication with the mixing chamber 3.

The two outer flanged necks 11 are connected by suitable joint connections to vertically disposed conveyor pipes 14 having the downwardly curved necks 15 which communicate through suitable connections with the top portions of the boiler, and thus establish communication between ends of the casing 10 and the upper portion of the boiler 1.

One end 9^a of the conveyor screw shaft 9 extends through the packing gland 16 in one end of the casing 10 to a suitable rotary steam turbine 17 which is in piping relation with the source of steam supply 18 from the boiler through the steam supply pipe 19 which is provided with the valve 19, that

controls the passage of steam to the said turbine 17. The opposite end 10^a of the tubular casing 10 is provided with a removable head 20 having a central socket 21 formed therein for the purpose of receiving and supporting the end 9^b of the conveyer screw shaft 9.

From the foregoing, it will be obvious that a rotation of the conveyer screw 8 by 10 the turbine 17 will cause the water in the mixing compartment 3 to flow down through the center neck 11 and outwardly in opposite directions through the tubular casing 10 to the outer water necks 11 from whence it will 15 be forced up into the pipes 14, through the necks 15 and into either side of the top of the boiler. Thus the cool water of the compartment 3 will be fed to the top of the boiler 1 and intermix with the hot water, 20 and then be sucked down around the fire tubes 22 thereby absorbing more heat, and then into the open end 4 of the chamber 3, where it again repeats the operation just described.

25 Having provided means for creating a circulation of water between the bottom and the top of the boiler a greater boiler efficiency will result because of the greater opportunity for heat transmission from the fire tubes 22 through which the heated gases pass from the fire box 23 to the smoke box 24, and thence out of the stack 25 to the atmosphere.

By referring to Fig. 1 of the drawings, it will be seen that since the compartment 3 is 30 closed at the front end and open at the rear end, and since the mechanical circulator draws water from the compartment, all water must pass through the opening 4 at the rear of the diaphragm 2 to get into said 35 compartment 3. When this flow is established, the water above the diaphragm will be drawn from the opening 4 to the back of said compartment thus always bringing comparatively hot water from the major 40 part of the boiler and mixing it with fresh water from the tender tank, and the coolest water in the bottom of the boiler which obviously results in aiding the increased steaming facilities of the boiler designed to be accomplished by this invention. The new 45 circulating condition is also augmented by the location of the arch tubes 26. These tubes are preferably placed immediately below the opening 4, and as usual are positioned in the 50 front leg 27 of the boiler. As these tubes 26 become steam generators, due to their location in the locomotive furnace 23, the water supplied thereto must also come from the front water leg 27, and this in time must be 55 replenished by water which also passes through the opening 4. Accordingly, since two separate and distinct currents, one through the compartment 3 and the other upwardly through the arch tubes 26, are supplied by water which must come from above

the diaphragm 2, it is further obvious that a rapid movement of water will take place in the vicinity of the lower tubes 22 within the boiler.

With this circulation system, it is preferred to discharge the feed water into the compartment 3, thus thoroughly mingling the cold water with the hot, which is much more to be desired than the present practice which is to discharge the cold feed water in 75 one place within the hot boiler.

It is quite possible to so design this circulator as to occupy a very inconspicuous place within the smoke box 24 of a locomotive as is shown in Figs. 4 and 5 of the 80 drawings. In the embodiment disclosed in these figures, the structure is identical with that disclosed in Figs. 1 to 3 inclusive except for the minor details and shape of the conveyer tubes 14, and the tubular conveyer casing 10, which are varied to adapt the invention to this particular part of a locomotive boiler, but in so doing, the structural features are not without the scope of the appended claims. The said conveyer tubes 14 90 are in communication at their lower ends with the outer necks 11, the same as in Fig. 3, but the said necks are curved to suit the location of the device. It will further be observed that said tubes 14 are in communication with the upper part of the boiler 1 at their other ends by means of a common fitting 28 which has the horizontally projecting boiler pipe connection 29. It will also be noted that the center neck 11 of the tubular casing 10 which is in communication with the compartment 3 is horizontal in this form of the invention instead of vertical as shown in Fig. 3.

With both types of the device it is preferable to locate boiler washout plugs 30, in such places that the bottom of the boiler can readily be cleaned of mud and such sediment as is usually found in locomotive boilers, after the same have been in service for 100 some time.

With a more uniform temperature of the water within the boiler it will readily be understood that flue leaks will be very much reduced, the bottom flues of the boiler will 115 perform more of the duties which they now do not perform and that the steaming facilities of the boiler will be much improved.

Without further description and elaboration it is thought that the many features 120 and advantages of the herein described water circulation system will be readily apparent, to those skilled in the art to which it belongs.

I claim:

1. A water circulating system for locomotive boilers including in combination with the boiler and fire-tubes, a separating diaphragm arranged below the fire tubes and extending across the boiler forming a mix- 130

ing compartment open at one end and closed at the other, means for establishing communication between said compartment and the top of the boiler, and operative means 5 for forcing the water through the latter.

2. A water circulating system for locomotive boilers, including in combination with the boiler having front and rear flue sheets, and longitudinal fire tubes connecting the 10 same, a diaphragm arranged beneath said fire tubes and extending transversely between the lower sides of the boiler, and having its front end meeting with the front flue sheet and its rear end terminating short 15 of the rear flue sheet to form a mixing compartment open at one end, water conveying means in communication with the said compartment formed on one side of the diaphragm and with the boiler on the other 20 side of the diaphragm, and power actuated means for forcing the water from the mixing

compartment to the major portion of the boiler.

3. A water circulating system for locomotive boilers including in combination 25 with the boiler having a mixing compartment formed therein, a tubular casing member having offset necks one of which is in communication with said compartment, a conveyer screw having oppositely pitched 30 flights and a shaft rotatably mounted in said casing, water carrying pipes communicating at one end with the other necks on the casing member and at the other end with the top of the boiler, and means for operating 35 said conveyer screw.

In testimony whereof I affix my signature in presence of two witnesses.

JOHN P. NEFF.
